FORGING MACHINE

William W. Criley, Cleveland, Ohio

Application March 15, 1932, Serial No. 598,963

5 Claims. (Cl. 74—585)

The purpose of this invention is to provide a safety release for forging machines. This type of release is, in general, well known and comprises a linkage system in a thrust member of a 5 forging machine by which the links are normally maintained in position to deliver a straight thrust but in which in case the thrust load is exceeded the linkage system will move so that the undelivered thrust movement will be absorbed in 10 repositioning the linkage members instead of breaking the machine. The mechanism used in this invention, in common with others which are directed to this type of safety arrangement, includes a strong spring which normally holds the 15 members of the linkage in extended position and upon which the stress at normal loads is less than the strength of the spring.

In earlier types of this sort of release mechanism the arrangement has usually been wasteful of space and difficult to assemble, and, furthermore, has necessitated a complete resetting of the spring pressure after every time that the safety arrangement has been disconnected to set the dies.

25 In the present invention I house this spring and its connections entirely in the actuating slide or cross head, and, furthermore, so arrange the parts that the spring pressure may be released, as for setting dies, and afterwards made effective 30 again without loss of the original adjustment. Also, after the spring has been removed it may be replaced at its former adjustment without needing any readjustment.

To the accomplishment of the foregoing and 35 related ends, said invention, then, consists of the means hereinafter fully described and particularly pointed out in the claims.

The annexed drawings and the following description set forth in detail certain mechanism 40 embodying the invention, such disclosed means constituting, however, but one of various mechanical forms in which the principle of the invention may be used.

In the accompanying drawings Fig. 1 is a partial plan view of a machine to which this invention is applied, the safety release being shown in normal position, that is, not released; Fig. 2 is a view similar to Fig. 1 showing the safety release acting under an overload when further movement of the die is stopped, the parts being 50 in extreme position but not final released position; Fig. 3 is an enlarged side elevation of the safety spring rod and associated parts, the spring itself being omitted from this figure; Fig. 4 is a plan view of the links, corresponding to Fig. 1, but

omitting the spring and spring mounting; Fig. 5 is a diagrammatic plan view of the position of parts in the intermediate collapsing position of Fig. 2; Fig. 6 corresponds to Fig. 5 but shows the final, fully collapsed position; and Fig. 7 is a 60 vertical section indicated by the line 7—7 of Fig. 4; and Fig. 8 is a vertical section indicated by the line 8—8 of Fig. 1.

In the preferred form here shown and described, the safety release is illustrated as applied to the die actuating slide 1 of a forging machine 2 of the type where in the header slide 3 movable longitudinally of the machine, and the die slide 4, transversely movable, are both actuated from a common transverse shaft 30, Fig. 1. 70 In the form here illustrated the slide 1 is moved to die-closing position by a cam 32 working against a roller 31, in a rearward extension 1A of the slide, and is retracted by another cam 33 which bears against the back of the slide, not 75 shown. The shaft 30 also drives the header slide 3 by a crank 34. This construction being well understood in the art, only the part of the machine to which this invention is directly applied is illustrated in detail. The die slide 4 is driven from 80 the die actuating slide 1 by a toggle composed of a bed plate knuckle 5 and die slide knuckle 6, pivoted respectively to the machine frame at 7 and to the die slide at 8 and joined by a pivot 9 to which a connecting link 10 from the actuating slide 1 85 is also pivoted, this link being pivoted at its other end at 11 to the safety release mechanism.

The safety mechanism includes a three-part linkage 12, 13, 14, a spring 15 and a spring mounting 16, 17, 18, all carried by the actuating slide 90 1. Under normal condition these parts do not move with relation to one another or to the actuating slide during the movement of the actuating slide, but under overload conditions the forward movement of the slide 1, instead of moving the 95 link 10 and thus spreading the toggle 5, 6, compresses the spring 15 and re-arranges the linkage against the opposition of the spring. The linkage is mounted upon the slide 1 by pivots 19 and 20, as shown in Fig. 8 and as indicated by shading 100 in Figs. 4, 5 and 6, fixed to the slide, and the link elements are mutually connected by movable pivots 11, 21 and 22. The linkage and the spring are interengaged by a trunnion block 23, the trunnions 25 of which turn in one arm 24 of a bell 105 crank lever on the pivot 20. In detail, the link element 12, known as the relief knuckle, is approximately triangular in plan view, having at each apex a bearing to receive, respectively, the pins of pivots 19, 11 and 21. The pivot 21 is con- 110

nected to the link 13, the other end of which is connected by the pivot 22 to the longer arm 14 of the bell crank lever, 14, 24, pivoted at 20 and having a shorter arm 24 with bearings at its outer end on journals 25 on the trunnion block 23. The arm 14 is known as the relief lever and the arm 24 as the relief lever arm. The latter is bifurcated, being conveniently constructed with a detachable top 24', as shown in Fig. 7. Thus by unfastening and lifting off the top plate 24' the trunnion block may be disconnected from the arm 24 by simply lifting out the rod 16 and the block 23 with it.

The relief spring 15, a compression coil spring, surrounds the rod 16 which is threaded at each end and which carries at one end a threaded washer 17 and at the other a nut and lock nut, 18 and 18'. These nuts are clear of the trunnion block 23 except when the pressure of the spring 15 is to be taken off the linkage. The trunnion block 23 is sleeved freely on the rod 16. The spring 15 bears at its opposite ends against an enlarged head 23' of the trunnion block and against the washer 17, respectively. Thus the linkage cannot collapse into the positions of Figs. 5 and 6 until the relief lever arm 24 has moved counterclockwise, compressing the spring 15. The short end of the rod 16 which extends to the left of the washer 17 is seated in the front wall of the actuating slide 1 as indicated at 26, Fig. 3. It will be noticed from Figs. 1 and 2 that the linkage is below the plane of the top edge of the cam slide. Provision is made in the sides and ends of the cam slides to allow these parts to assume the positions shown.

A preferred form of mechanism to limit the clockwise movement of the pivot 22 about the pivot 20, and thus to keep it slightly below dead center so that the joint at 22 will break outward, toward the header slide, instead of toward the spring, comprises a stop 27 formed on one edge of a shelf 28 in the upper part of the slide 1. The upper end of the pivot pin 22 is correspondingly flattened as shown in Figs. 1 and 2 to engage against this stop. Thus the movement of the trunnion block 23 to the right, Figs. 1 and 3, is limited by the stop 27 and not by the nut 18.

A description of the operation of the device follows. Under normal conditions the spring 15 and the linkage 12, 13, 14 maintain the positions shown in Figs. 1 and 4 in every position of the travel of the actuating slide 1. Under overload continued forward movement of the slide 1 swings the relief knuckle 12 counterclockwise about the pivot 19, breaks the toggle 13, 14 away from the stop 27, swings the bell crank 14, 24 counterclockwise, and moves the trunnions 25 to the left, compressing the spring 15. This is the intermediate position, shown in Fig. 5, passed through on the way to the full collapse position of Fig. 6.

When the relief knuckle 12 has swung to the position of Fig. 5 the pivots 19, 21, 22 are aligned with 21 a trifle to the right of the line 19—22, so that a toggle exists here which will break to the right under the pressure of the spring 15, either with or without further resistance of the link 10. The longitudinal component of movement of the pivot 11 from the position of Fig. 4 to that of Fig. 6 is equal to the entire forward travel of the actuating slide 1, so that even if an obstruction to the die movement is encountered when the movable die is in full open position, no damage will be done.

To re-set the safety mechanism from the position of Fig. 6 to that of Fig. 4, the slide 1 is run

rearward, to the right in the figures. The inertia of the movable die holding the link 10 and pivot 11 swings the knuckle 12 clockwise about the pivot 19 just enough to break the toggle joint at 21 over dead center and slightly to the left of the position of Fig. 5, whereupon the expansion of the spring 15 snaps the linkage back to the position of Fig. 4. To throw out the safety device for setting dies the spring pressure is taken off the linkage by setting up on the nut 18 until the spring thrust is taken off the linkage and held entirely by the nut. Then by moving the pivot 22 by hand away from the stop 27 the safety can be thrown out so that the travel of the actuating slide can be taken up in the linkage while the movable die remains full open on the forward stroke of the header slide, as is necessary at times in the operations of setting dies and centering tools. This does not alter the spring adjustment, which is governed solely by the position of the washer 17. Thus again slackening off the nut 18 to the position of Fig. 3 leaves the safety all ready to work again without readjustment.

To change the spring adjustment the nut 18' is run up to lock with the nut 18 and the two are then used to take a wrench for turning the rod 16. The set screw of the washer 17 having been released and this washer having been held against rotation, rotation of the rod 16 moves the washer in the proper direction. When the correct setting is had the set screw is locked down and the nuts 18, 18' slackened off.

In dismounting the safety spring and its connections, the nut 18 is tightened up to move the trunnion block in and so take the pressure of the spring off the linkage, the relief lever arm top 24' is removed from the relief lever arm 24 and the bottom trunnion 25 is lifted out of its bearing. The socket 26 holds the end of the rod 16 with side clearance, allowing the needed freedom of movement for these operations. The rod 16, with the spring 15 thereon, is taken out and the spring pressure gradually released by backing off the nut 18 until the spring is free, after which the nut can be taken off the rod, the trunnion 23 taken off, and the spring removed.

Other modes of applying the principles of my invention may be employed instead of the one explained, change being made as regards the mechanism herein disclosed, provided the means stated by any of the following claims or the equivalent of such stated means be employed.

I therefore particularly point out and distinctly claim as my invention:

1. A safety device for a mechanism of the type described comprising a plurality of interconnected toggles on a common movable power-transmitting support, said toggles being adapted to transmit thrust, and resilient means for maintaining said toggles extended, said toggle system and said resilient means being enclosed in common limits, a mounting for said resilient means comprising a carrying element and a connector to said toggle system, said carrying element being carried at one end by said connector and at the other by said common support, said connector being movable relatively to said support by force applied to said toggle system and also by the force of said resilient means, and means for confining the force of said resilient means to stress upon the carrying element.

2. A reciprocating safety mechanism for transmitting thrust, comprising in combination a slide, driving and driven connections thereto, a toggle system within said slide, and means for prevent-

ing collapse of said system under predetermined loads, said means including a spring, a carrier whereon said spring is mounted, a connecting member between said spring and said toggle system freely slidable on said carrier, another element on said carrier movable longitudinally thereof and engageable with said connecting member, and longitudinally successive positive contact means between said last-named element 10 and said carrier.

3. In a safety mechanism of the type comprising a thrust-transmitting slide, two interconnected toggles pivoted thereto and a spring adapted to hold said toggles immovable against ordinary working loads, spring mounting means comprising a rod disposed longitudinally through said spring, a threaded washer on one end of said rod constituting an abutment for said spring, a 15 slidable trunnion block on the other end of said arm and pivoted to a toggle link, a nut threaded on the other end of said rod and movable into engagement with said block to take the pressure of said spring off said toggle link, and removable connecting means between said link and said 20 trunnion block.

4. In a forging machine having a die actuating slide, a safety release comprising a linkage and a spring all mounted on said slide and contained therewithin, a rod, said spring being mounted 25

30

upon said rod and said rod being mounted at one end in said slide, an end seat for said spring on said rod and adjacent one end thereof, and a block slidable on the other end, said spring tending to move said block in a direction away from 80 said end seat, said linkage including an arm pivoted to said block, and a stop on said slide adapted to coast with said linkage to limit the movement impressed on the linkage by said spring.

5. A safety device for a mechanism of the type described comprising a thrust-transmitting slide including a housing portion, a front and a rear pivot thereon, two interconnected toggles, one member of each toggle being carried by one of said pivots, said toggles being adapted to transmit thrust, and resilient means for maintaining said toggles extended, said resilient means being disposed immediately adjacent the toggle system and housed entirely within the housing of said system, an abutment on said housing in advance 90 of said front pivot, and a trunnion pivoted to an arm of said toggle system, the pressure of said resilient means being taken at one end on said abutment and at the other end on said trunnion, said resilient means being compressible when the 95 thrust transmitted by said slide meets with extraordinary resistance.
